US0D1026336S

(12) **United States Design Patent** (10) **Patent No.:** **US D1,026,336 S**
(45) **Date of Patent:** **** May 7, 2024**

(54) **HELMET**

(71) Applicant: **SHOEI CO., LTD.**, Tokyo (JP)

(72) Inventor: **Taku Nimura**, Tokyo (JP)

(73) Assignee: **SHOEI Co., Ltd.**, Tokyo (JP)

(**) Term: **15 Years**

(21) Appl. No.: **35/516,128**

(22) Filed: **Jan. 25, 2022**

(80) **Hague Agreement Data**

Int. Filing Date: **Jan. 25, 2022**

Int. Reg. No.: **DM/218738**

Int. Reg. Date: **Jan. 25, 2022**

Int. Reg. Pub. Date: **Jan. 27, 2023**

(30) **Foreign Application Priority Data**

Nov. 9, 2021 (JP) ..... 2021-024471 D
Nov. 9, 2021 (JP) ..... 2021-024472 D
